UNITED STATES PATENT OFFICE

2,260,292

RAILWAY SIGNALING SYSTEM

Andrew Brown and Thomas Alfred Marshall,
London, England, assignors to International
Standard Electric Corporation, New York, N. Y.

Application October 25, 1939, Serial No. 301,308
In Great Britain October 7, 1938

2 Claims. (Cl. 246—134)

This invention relates to railway signal and points control equipment.

In railway signal and points practice, it is necessary to provide stringent checks between the various signals and points in order to determine, when setting up a route and freeing it to on-coming traffic, that all signals and points which are inter-related with those directly concerned in setting up the route are in such positions that no other conflicting route is simultaneously set up and freed, and that no other possible source of interference or trouble exists.

In United States Patent No. 2,241,906, granted May 13, 1941, and British Patent 496,495, accepted November 30, 1938, there is disclosed a railway signal and points control equipment comprising a number of panel control keys of which any one can be set to select a certain route, a number of multi-position switches of which any one can be set in response to the setting of a panel control key to an off-normal position distinctive of the said selected route, and means for setting the appropriate track equipment, i. e., the signals and/or points, in accordance with the setting of the said multi-position switch. Each multi-position switch, which may be of the type used in the rotary system of automatic telephony and known as sequence switches, includes a normally disengaged clutch which can be electro-magnetically engaged with a rotating driving shaft. The electrical circuit for causing clutch engagement in response to the setting of the panel control key includes contacts which can only be closed provided that no other multi-position switch is in a position to set up a conflicting route, and further contacts which can only be closed provided that no other multi-position switch is in motion. The object of the present invention is to reduce the number of relays and relay contacts associated with each multi-position switch as compared with the systems described in Patent No. 2,241,906.

The invention will be clearly understood from the following description of one embodiment thereof shown in the accompanying drawings, which shows the control circuits of one of the five sequence switches of the interlocking system described in Patent No. 2,241,906, together with the lockout circuit for all the sequence switches.

In prior British patent specification #496,495, a group of RC contacts was required in series with each clutch magnet in order to prevent simultaneous rotation of any two switches carry-

ing conflicting routes. This system would still permit the simultaneous rotation of two sequence switches where none of the routes on one sequence switch conflicts with any of the routes on the other.

It is now proposed to provide a complete lock-out between sequence-switch driving-clutches, so that it will be impossible for any two switches to revolve simultaneously.

It is found in practice that the additional delay occasioned by preventing the simultaneous rotation of non-conflicting switches, is quite negligible and is easily outweighed by the simplification obtained by the adoption of a universal lock-out circuit.

Fig. 1 illustrates diagrammatically a lock-out circuit arrangement in accordance with my invention.

Figs. 2 and 2A taken together show the control circuit for sequence switch 1 of Fig. 1.

Since the present invention relates primarily to the control mechanism for the sequence switch clutches the general circuit has been shown only diagrammatically in Fig. 1. The five sequence or other rotary switches are shown at 1, 2, 3, 4 and 5. No illustration of the interlocking cam arrangements of these switches is shown and the selective operating keys are merely indicated schematically since the details of these parts are unimportant to the invention. The circuits through switches 1—5 have been indicated by straight lines except in the output of switch 5 where separate lines to relays 1R, 2R, 3R, 4R, and 5R are illustrated. These relays correspond to the R relays described in the aforementioned application and are used in completing a circuit for the motor start relay MS.

When a desired route is selected it is necessary that one or more of sequence switches 1—5 be rotated to the proper position for establishing such route. However, if a conflicting route is in existence at the time, the circuit for the R relay corresponding to the selected route is not completed so that the selected route cannot be set up so long as the conflict exists.

It is also desired that if a route is in the process of being set up by rotation of a sequence switch, initiation of selection of a second route which may conflict with said route being set up should not be effected. In accordance with this invention such initiation is prevented by provision of an interlock in the clutch magnets 1RC, 2RC, 3RC, 4RC, 5RC, so that only one sequence switch may be in motion at one time.

Movement of switches 1, 2, 3, 4, 5 is effected by means of a motor M under control of a motor start magnet MS through corresponding clutches selectively operated by clutch magnets 1RC, 2RC, 3RC, 4RC, 5RC, respectively.

Suppose a selection of route is made such that rotation of switch 1 is necessary to set up the route. If no conflicting route exists at this time a circuit will be established upon operation of the route selecting key, indicated diagrammatically in Figs. 2 and 2A, for relay 1R, from positive, cams of one or more of sequence switches 1—5, winding of relay 1R to negative. Relay 1R will operate closing its contacts 1r2 establishing a circuit for clutch magnet 1RC and motor start relay MS from positive, winding magnet 1RC, normally closed contacts 2rc2, 3rc2, 4rc2, 5rc2 winding MS to negative. Energization of MS will start the motor and energization of RC will operate its clutch causing switch 1 to rotate until the circuit for 1R is opened by the switch reaching its selected position. Deenergization of relay 1R opens the circuit of magnet 1RC which releases the clutch of switch 1, stopping its rotation upon deenergization. Magnet 1RC while energized also opens its contacts 1rc preventing completion of circuits for magnets 2RC, 3RC, 4RC, 5RC while switch 1 is in operation.

Suppose now the selected route calls for operation of switch 3 after switch 1 has been positioned. A circuit will thus be established for relay 3R assuming no conflict exists in a manner similar to that described for 1R.

Relay 3R operates closing its normally open contacts 3r2 and establishing a circuit for clutch magnet 3RC and motor start relay MS from positive, normally closed contacts 1rc, 2rc, contact 3r2, winding of relay 3RC, normally closed contacts 4rc2, 5rc2, winding of relay MS to negative. Relay MS and magnet 3RC are energized operating switch 3 as indicated. At the same time magnet 3RC opens its normally closed contacts 3rc2, 3rc, preventing completion of any circuits for magnets 1RC and 2RC at the former and for magnets 4RC and 5RC at the latter.

It can therefore be seen that each magnet upon operation prevents operation of the others by breaking the positive lead for magnets to its right and breaking the negative lead for magnets to its left. Accordingly, only one switch can be in motion at any one time.

In Figs. 2 and 2A a more specific circuit diagram showing the control circuit for sequence switch 1 is shown. It should be understood that a similar circuit is utilized for each of the sequence switches.

A brief explanation of the conventions used in Figs. 2 and 2A will serve to simplify the description. The contacts controlled by the various relays are shown by open arrowheads, those above the line indicating front contacts and those below the line indicating back contacts. The arrowheads contacting the line indicate that the contacts are normally closed and those spaced from the line indicate contacts normally open. The relays and armatures are separated in order not to unduly complicate the circuits, the relays being indicated generally by upper case letters and their contacts by lower case letters, corresponding letters being used for the relays and contacts.

The five sequence switches are designated by numbers 1, 2, 3, 4 and 5, and the separate cams thereof by a letter following the number as 2A,

3F, etc. The contact positions at which the cam closes a circuit are generally indicated by the numerals following the letter. Other conventions for the cams are set forth below.

5 The well known sequence switch is of the general type illustrated in the patent to Reynolds 1,127,808, February 9, 1915, and may consist of a plurality of discs or cams rotatable with a driving spindle and cooperating brushes. The discs 10 or cams may be of metal separated by insulation, the metal parts being cut away in part so that in certain positions the brushes associated with a particular disc do not close a circuit. The switch spindle is rotated to a number of positions corresponding to desired settings and in each position 15 will complete selected ones of the circuits associated therewith. In the preferred arrangement each switch is provided with a magnetically controlled clutch for coupling the spindle to a motor for securing the desired drive.

The convention shown for cam A represents the master control cam of the sequence switch cut to break contact in each of the respective route setting positions.

25 The convention shown for cam L represents a cam making contact only in the position specified, i. e. the "home" position. The convention shown for cam F, of sequence switch 3, represents a cam making contact in every position except those 30 specified, i. e. the circuit is broken when the sequence switch is in the positions corresponding to routes 1 or 3, but made in every other position. The convention shown for cams D and E in sequence switch 2 represents two adjacent copper 35 cams connected together by metal rivets and each breaking their appropriate circuits in positions 15 and 16, and 2 and 4 respectively.

Similarly, the pairs of cams on sequence switch 40 No. 1, B and C, and D and E are riveted together and the adjacent pairs B—C, D—E and F are connected on the sequence switch rotor without the need for external wiring. The wipers shown 45 contacting with cam C would make contact continuously from the "home" position to route 6 and from the "home" position to route 5 respectively.

Consider the procedure for setting up a route.

Let us assume that the signalman attempts 50 to set up a route No. 5 indicated by 5(R) in Fig. 2 by reversing panel control switch No. 5. The individual panel switches indicated by a numeral and (R) are normally open and each switch (R) is mechanically coupled with a normally closed switch (N), Fig. 2A, as described in British Patent 496,495, referred to above. Assuming that No. 1 sequence switch is in its "home" position and that sequence switches 3, 4 and 2 are not standing in the conflicting route positions 1, 3, 8, 9, 15 or 16, then a circuit will be completed for the relay 1R: from positive, over cam F of sequence switch 3, cam F of sequence switch 4, cam D of sequence switch 2, panel switch 5(R) reversed, cam B of sequence switch 1 in the "home" position, cam L of sequence switch 1, coil of relay 1R, to negative. Relay 1R is operated and will energise the clutch magnet 1RC for sequence switch No. 1 provided that no other clutch magnet is then energised.

The circuit for sequence switch is thus completed and the other sequence switches are removed from circuit, as explained in connection with Fig. 1.

When the clutch magnet 1RC operates in response to the relay 1R, the sequence switch 1 will

revolve out of the "home" position H and the circuit already described for relay IR will be broken by cam 1B. The relay IR will remain energised over the A cam until the sequence switch reaches the position corresponding to route 5, whereupon relay IR, and consequently clutch magnet IRC, will be deenergised and the switch will come to rest.

The relay IPR is then operated over back contacts Irc3, Fig. 2, cam 1X in route position 5, panel switch 5, cams 2D, 4F and 3F provided that circuits through the interlocking sequence switches and the panel control key remain intact. Sequence switch 1 in position 5, in conjunction with relay IPR operated, will thereupon set the necessary points and clear the signal for route 5, subject to the usual point and signal control requirements. The circuit originally traced for relay IR was broken by cam 1L which is no longer in its "home" position and the sequence switch can only be driven "home" by contacts Iyr2 after proving that it is safe for route 5 to be restored to normal.

The restoration of the route setting will now be considered referring more particularly to Fig. 2A. As soon as panel switch 5(R) is moved out of reverse position the circuit for relay IPR, Fig. 2, will be broken and the circuit at 5(N) closed. Relay IPR will release and contacts 5/6/1h, Fig. 2A, will be closed by circuit arrangements not shown, since they have no bearing on the present invention.

A circuit is then provided for relay IYR, from positive, contact Irc4, cam N of sequence switch 1, panel switch 5(N) in normal position, contacts 5/6/1h, track contacts 105TR, 104TR, winding IYR to negative. In event track 3 is occupied contact 3SR will complete a circuit for IYR independently of track relays 105TR, 104TR.

Energization of relay IYR closes a circuit for relay IR at Iyr2, Fig. 2, independently of cam A of switch 1 to start the switch after which it will be returned to home position under control of cam A of switch 1.

The details for alternative circuit in Figs. 2 and 2A are not described since they are not needed for an understanding of this invention. The more or less complete circuit is shown, however, to clearly show the relation of this circuit

with respect to that described in application Ser. No. 209,198 mentioned above.

What is claimed is:

1. In railway routing control equipment having a manual means for selecting a route, a plurality of multi-position switches of which any one can be set to a position distinctive of the said selected route, an electromagnetically operated clutch for each multi-position switch drive means, means for selectively operating said multi-position switches comprising clutch magnets selectively energised in response to the setting of the manual selecting means for operating a corresponding one of said clutches for coupling one of said switches to said driven means to drive the said multi-position switch to the route-distinctive position, a common pair of feed lines across which said clutch magnets are arranged in parallel, the connections to one line being in reverse order to the connections to the other with respect to a feed terminal at one end of each line for the clutch magnets, and two pairs of normally-closed contacts which are opened when the respective clutch magnet is energised, connected one in each feed line between the junction to the feed line of the said magnet and the junction to the feed line of the next magnet away from the feed terminal.
2. In railway routing control equipment having manual means for selecting a route, a plurality of multi-position switches of which any one can be set to a position distinctive of said selected route, an electromagnetically operated clutch for each multi-position switch, drive means for said clutches, means for selectively operating said multi-position switches comprising electromagnetic clutch operating means for selectively operating said clutches to couple a selected one of said switches to said drive means, circuit connections for said clutch operating means, means responsive to operation of said manual means for completing an operating circuit for a selected one of said electromagnetic clutch operating means, and means responsive to operation of said selected clutch operating means for preventing completion of an operating circuit for the other clutch operating means.

ANDREW BROWN.

THOMAS ALFRED MARSHALL.
